UNITED STATES PATENT OFFICE.

HOWARD E. WATKINS, OF NEW YORK, N. Y., ASSIGNOR TO OXLEY ENOS COMPANY, OF NEW YORK, N. Y., A CORPORATION OF NEW YORK.

DESIGN FOR A SHELL FOR LIGHTING-FIXTURES.

SPECIFICATION forming part of Design No. 36,503, dated August 18, 1903.

Application filed July 14, 1903. Serial No. 165,531. Term of patent 14 years.

To all whom it may concern:

Be it known that I, HOWARD E. WATKINS, a citizen of the United States, residing at New York city, New York county, State of New York, have invented a certain new and ornamental Design for a Shell for Lighting-Fixtures, of which the following is a full, clear, and exact description.

My invention relates to a design for a shell for lighting-fixtures, such as wall-brackets and chandeliers.

In the drawings, Figure 1 represents in elevation a shell embodying my design formed

of sheet metal, oval in outline, and having a central perforation. Fig. 2 is a side elevation showing the outline and radiating lines.

What I claim as new, and desire to secure by Letters Patent, is—

The ornamental design for a shell for lighting-fixtures, as herein shown.

Signed at New York, N. Y., this 2d day of July, 1903.

HOWARD E. WATKINS.
